UNITED STATES PATENT OFFICE.

CHARLES ADAMS, OF NEW KENSINGTON, PENNSYLVANIA.

DESIGN FOR A BOTTLE OR SIMILAR ARTICLE OF MANUFACTURE.

Application filed December 22, 1927. Serial No. 24,582. Term of patent 14 years.

To all whom it may concern:

Be it known that I, CHARLES ADAMS, a citizen of the United States, residing at New Kensington, in the county of Westmoreland and State of Pennsylvania, have invented a new, original, and ornamental Design for a Bottle or Similar Article of Manufacture, of which the following is a specification, reference being had to the accompanying drawing.

I claim:

The ornamental design for a bottle or similar article of manufacture, as shown.

December 9th, 1927.

CHARLES ADAMS.
